JAY W. FARNOFF, OF BUFFALO, NEW YORK, ASSIGNOR OF ONE-THIRD
TO JOHN H. CASLER AND ONE-THIRD TO ARTHUR H. RICE, OF BUF-
FALO, NEW YORK.

GAS-BURNER.

No. 799,842.

Specification of Letters Patent.

Patented Sept. 19, 1905.

Application filed May 19, 1905. Serial No. 261,130.

To all whom it may concern:

Be it known that I, JAY W. FARNOFF, a citizen of the United States, residing at Buffalo, in the county of Erie and State of New York, have invented a new and useful Improvement 5 in Gas-Burners, of which the following is a specification.

This invention relates more particularly to a gas-burner in which the mantle is supported 10 in a pendent or inverted position.

The object of this invention is the production of a burner of this character which is extremely simple in construction and neat in appearance and which produces a very powerful 15 light.

In the accompanying drawings, Figure 1 is a vertical section of my improved gas-burner. Figs. 2 and 3 are horizontal sections thereof in lines 2 2 and 3 3, Fig. 1, respectively. Fig. 20 4 is a sectional elevation, on an enlarged scale, of the gas-valve. Fig. 5 is a cross-section thereof in line 5 5, Fig. 4. Fig. 6 is a fragmentary sectional elevation showing a modification of the means for adjustably supporting 25 the mantle from the main or mixing tube.

Similar letters of reference indicate corresponding parts throughout the several views.

A represents the vertical main or mixing tube, which preferably tapers downwardly 30 and is constructed of lavite, although the same may also be made of metal or any other suitable material. Upon the lower end of the mixing-tube the mantle B is supported in a pendent position and preferably by the following means: C represents a metal ring, to 35 the lower end of which the upper or open end of the mantle is secured and which is provided on diametrically opposite sides with laterally-projecting supporting-ears c, that are formed 40 out of the body of the ring by slitting the upper edge of the same vertically and then bending the parts between the slits downwardly, thereby forming the ears and also forming recesses c' in the upper edge of the body in line 45 with said ears. D represents a sleeve which carries the mantle and is capable of vertical adjustment on the mixing-tube. This adjustment is preferably effected by providing the sleeve with an internal thread and engaging 50 the same with an external thread on the lower end of the mixing-tube, as shown in Fig. 1. Projecting outwardly from opposite sides of the sleeve are two horizontal arms d, each of 55 which has a depending lug d' at its outer end.

E represents horizontal set-screws, which work 55 in threaded openings in the lugs d'. In assembling the parts the adjusting-sleeve is first screwed onto the mixing-tube. The supporting-ring of the mantle is next placed around the mixing-tube so that its recesses receive the 60 arms d of the sleeve and the ears thereof bear against the under side of said arms. Upon now tightening the set-screws so that they engage with the under side of said lugs adjacent to the supporting-ring the latter is secured to the tube. The ears of the mantle-supporting ring preferably incline from their outer toward their inner ends, and the set-screws are so arranged that they bear against 65 the inclined under sides of the ears, as shown 70 in Fig. 1. By thus engaging the arms d with the recesses of the mantle-ring and the set-screws with the ears thereof this ring and its mantle are securely connected with the mixing-tube and the burner is permitted to be 75 tilted at an angle without liability of displacing the mantle relatively to the mixing-tube. By screwing the supporting-sleeve up or down on the mixing-tube mantles of varying length 80 may be adjusted so as to stand centrally in the globe F, which surrounds the mantle.

While I prefer the construction of mantle supporting and adjusting device shown in Figs. 1 and 3, the means for supporting the mantle in the globe may be varied. For instance, as shown in Fig. 6, the adjusting-sleeve D' may be provided with a plurality of laterally-extending arms d'', having seats on 85 their upper sides which are adapted to receive the inwardly-projecting ears c' of a mantle- 90 supporting ring C'.

G represents the holder or support for the globe. This holder is provided with a central opening, whereby the same may be slipped over the upper end of the mixing-tube and engaged with an upwardly-facing shoulder g thereon. At its periphery the holder is provided with a depending flange g', which surrounds the upper end of the globe and carries 95 fastening-screws g'', which engage with an external groove in the upper edge of the globe for holding the same in place, as shown in Fig. 1. The top of the globe-holder is of skeleton form, and the globe is provided at its bottom with a central opening h and in 100 its top around the holder with openings h' to permit the air to circulate freely through the globe and prevent excessive heating thereof.

Upon the upper end of the mixing-tube is mounted an upwardly-flaring mixing chamber or dome I, in which the gas and air are mixed before being conducted to the mantle 5 by the mixing-tube. Around the mixing-dome is an upwardly-flaring deflector J, whereby the hot gas and burned products rising from the mantle and globe are carried outwardly and prevented from mixing with the fresh air 10 entering the mixing-dome. The lower small ends of the mixing-dome and deflector bear against each other; but their upper ends are separated by an intervening space. The preferred means of securing the deflector and 15 mixing-dome to the mixing-tube consists in providing the lower end of the deflector with a collar j, which surrounds the upper end of the mixing-tube and bears against the upper side of the globe-holder, and providing the lower 20 end of the mixing-dome with an upturned and internally-screw-threaded collar i, which engages with an external thread on the upper end of the mixing-tube. Upon tightening the mixing-dome on the mixing-tube the collar of the deflector is clamped between the 25 dome and the globe-holder, thereby holding these parts firmly on the mixing-tube. At its upper end the mixing-dome is provided with an outwardly-projecting annular flange K, 30 which bears at its edge against the inner side of the deflector, at the upper end thereof. Extending horizontally over the top of the mixing-dome and its flange is a top plate L, having a central opening and a plurality of segmental 35 openings l around the central opening which place the dome in communication with the atmosphere. The dome-flange and the top plate are securely united to the deflector by a head or seam m, formed on the upper edge of the 40 deflector and turning upwardly and inwardly over the outer edges of the superposed flange K and top plate L, as shown in Figs. 1 and 2. The case or body N of a gas-valve extends 45 downwardly through the central opening of the top plate and is secured therein, preferably by providing said case and opening with coöperating external and internal screw-threads, respectively. The chamber of this case has the inlet at its upper end connected 50 with a gas-supply pipe o, while the outlet-nozzle at its lower end is provided with an internal valve-seat p. Within the chamber of the valve-case is a vertically-movable and longitudinally-grooved valve-stem Q, having a 55 valve q at its lower end which moves toward and from the seat p for opening or closing the outlet-nozzle. In its side the valve-stem is provided with a transverse groove q', which receives a crank pin or wrist r. The latter is 60 arranged eccentrically on the inner end of a horizontal shaft or spindle R, which is journaled in a bearing in the adjacent part of the valve-case. Outside of the case the spindle is provided with a thumb piece or button r' 65 for turning the same. The spindle is held

against axial movement in its bearing by means of a seat s, which is formed by punch-marking, indenting, or pressing the stock of the valve-casing inwardly into an annular groove s' in the spindle, as shown in Fig. 5. 70 Upon turning the spindle the position of the valve relatively to its seat may be varied as may be necessary to produce the proper mixture of the same in the dome with the air entering through the openings l. In order to 75 enable the volume of air to be also regulated, a rotatable shutter T is pivoted on the valve-case between a shoulder thereon and the upper side of the top plate and provided with a plurality of wings t, which cover the air-openings l more or less, according as the shutter is turned. For convenience in manipulating the air-shutter the same is provided with a finger piece or lip t', as shown in Figs. 1 and 2. 80

Within the upper part of the mixing-tube is a guard-tube U, which prevents the flame at the mantle of the burner from flashing backward and igniting the gas at the valve. This guard-tube tapers downwardly and fits 90 tightly at its upper end in the upper end of the mixing-tube, while its lower end is separated therefrom by an intervening annular space. For convenience in assembling the guard-tube with the other parts of the burner 95 the upper end thereof is provided with an external annular flange u, which bears against the upper end of the mixing-tube, and thus serves as a stop for limiting the downward movement of the guard-tube in the mixing-tube. If the flame tends to flash back, the same passes around the outer side of the guard-tube instead of upward through the center thereof, thereby preventing the flame from reaching the gas-regulating valve. 100

I claim as my invention—

1. A gas-burner comprising a mixing-tube, and means for supporting a mantle on said tube comprising a ring carrying said mantle and having laterally-projecting ears, arms supported on said tube, and screws mounted on said arms and engaging with the under side of said ears, substantially as set forth. 110
2. A gas-burner comprising a mixing-tube, and means for supporting a mantle on said tube comprising a ring carrying said mantle and having laterally-projecting ears and recesses above said ears, arms supported on said tube and engaging with the recesses of said ring, and screws mounted on said arms and engaging with the under side of said ears, substantially as set forth. 115
3. A gas-burner comprising a mixing-tube, and means for supporting a mantle on said tube comprising a ring carrying said mantle 120 and having laterally-projecting ears and recesses above said ears, arms supported on said tube and engaging with the recesses of said ring, lugs depending from the outer ends of said arms, and screws arranged in said lugs 125 130

and engaging with the under side of said ears, substantially as set forth.

4. A gas-burner comprising a mixing-tube having an external screw-thread on its lower end, and means for adjustably and detachably connecting a mantle with said tube comprising an adjusting-sleeve having an internal screw-thread which engages with the thread of said tube, arms projecting laterally from said sleeve and having depending lugs at their ends, a supporting-ring secured to the upper end of a mantle and provided with outwardly-projecting inclined ears which engage with the under side of said arms and with recesses above said ears which receive said arms, and screws arranged in said lugs and engaging with the inclined under sides of said ears, substantially as set forth.

5. A gas-burner comprising a mixing-tube, a deflector, a collar arranged on said deflector and supported on said tube, a mixing-chamber engaging its lower end with said deflector, and a screw-joint connecting said chamber with the mixing-tube, substantially as set forth.

25 6. A gas-burner comprising a mixing-tube, an upwardly-facing shoulder formed on said tube, an external screw-thread formed on said tube above said shoulder, a globe, a holder supporting the globe and resting on said shoulder, a mixing-chamber, an internally-threaded collar arranged on the mixing-chamber and engaging with the thread of said tube, a deflector surrounding said mixing-chamber, a collar arranged on said deflector and mounted on said tube between the globe-holder and the collar of said mixing-chamber, substantially as set forth.

7. A gas-burner comprising a mixing-tube, an upwardly-flaring mixing-chamber connected at its lower end to the upper end of said tube, and an upwardly-flaring deflector engaging the mixing-chamber at its lower end but separated therefrom at its upper end by an intervening space, substantially as set forth.

45 8. A gas-burner comprising a mixing-tube, an upwardly-flaring mixing-chamber connected at its lower end to the upper end of said tube, an upwardly-flaring deflector engaging the mixing-chamber at its lower end but separated therefrom at its upper end by an intervening space, and a flange connecting the upper edges of the mixing-chamber and the deflector, substantially as set forth.

9. A gas-burner comprising a mixing-tube, 55 an upwardly-flaring mixing-chamber secured to said tube, an upwardly-flaring deflector surrounding said chamber and separated there-

from at its upper end, and a top plate connected with the upper ends of said chamber and deflector and provided with openings above 60 said chamber, substantially as set forth.

10. A gas-burner comprising a mixing-tube, an upwardly-flaring deflector surrounding said chamber and separated therefrom at its upper end, a flange extending laterally from the upper end of said chamber to said deflector, a top plate arranged above said flange and chamber and provided with openings above the latter, and an inwardly-turned seam or flange formed on the upper end of said deflector and 70 engaging over said top plate, substantially as set forth.

11. A gas-burner comprising a mixing-tube, an upwardly-flaring mixing-chamber connected with the upper end of said tube, an upwardly-flaring deflector separated at its upper end from said chamber, a top plate connecting the upper ends of said deflector and chamber and provided above the latter with a central opening and around said central opening 80 with a plurality of air-openings, a gas-valve case arranged in said central opening, and a shutter pivoted on said casing and controlling said air-openings, substantially as set forth.

12. A gas-burner comprising a mixing-tube, 85 an upwardly-flaring mixing-chamber connected with said tube, and a downwardly-tapering guard-tube arranged in said mixing-tube, substantially as set forth.

13. A gas-burner comprising a mixing-tube, 90 an upwardly-flaring mixing-chamber connected with said tube, and a downwardly-tapering guard-tube arranged in said mixing-tube and having a flange at its upper end which rests on the upper end of said mixing-tube, substantially as set forth.

14. A gas-burner comprising a valve-case containing a chamber having an inlet, an outlet and a valve-seat, a stem arranged in said chamber and provided with a valve which cooperates with said seat and with a transverse recess in its side, a spindle journaled in a bearing in the side of the casing and having an annular groove within said bearing and provided at its inner end with a crank-pin which 100 engages with said recess, and a seat formed on said casing and entering said groove, substantially as set forth.

Witness my hand this 17th day of May, 1905.

JAY W. FARNOFF.
